UNITED STATES PATENT OFFICE.

CLINTON W. SCHALL, OF COLUMBUS, OHIO.

BUILDING SLAB.

Application filed April 17, 1924. Serial No. 707,085.

To all whom it may concern:

Be it known that I, CLINTON W. SCHALL, a citizen of the United States, residing at Columbus, in the county of Franklin and 5 State of Ohio, have invented a certain new and useful Improvement in Building Slabs, of which the following is a specification.

The object of this invention is to provide an improved slab of concrete designed for 10 the rapid and economical construction of a wall. A further object is to provide a slab so constructed that when plastered upon its inner side or covered with plaster board or other material air spaces are provided for 15 both horizontal and vertical circulation of air between the plaster side and the outer side so that dryness of the interior of the building will be promoted and conduction of heat either from the interior or to the 20 interior lessened.

The invention is embodied in the example herein shown and described, the features of novelty being finally claimed.

In the accompanying drawing—
95 Fig. 1 is a view in elevation of the inner side of the slab.

Fig. 2 is an elevation of the right hand edge of the slab as seen in Fig. 1.

Fig. 3 is an elevation showing three of the 30 slabs set edge to edge as in erecting a wall.

Fig. 4 is a horizontal section on the line IV—IV Fig. 1 but on a magnified scale.

Fig. 5 is a detail in horizontal sectional view of two fractions of an outer wall showing 35 how the vertical edges of two slabs can be tied together.

Fig. 6 is a detail with parts in vertical section showing how the concrete of the slab is reinforced and also showing how plaster 40 board or plaster lath can be connected to the studding members of the slab.

In the views 7 designates the outer wall of the slab which is usually designed to be of somewhat more than room height and of 45 about the width of two studding spaces. The characters 8 designates the studding members which are spaced apart at the usual or desired studding distance. Horizontally between the studding members and at each 50 side beyond the studdings on each slab is a web 9 to support a beam of timber for a joist or rafter. The lower and upper ends of the slab are formed with flanges 10 and 11 respectively to rest on the buildings

foundation and receive superposed slabs for 55 the story above, such flanges also bracing the slab and the studding. The edges of the studding members are formed with several curved recesses 12 to permit air to circulate horizontally between the studding and 60 throughout the wall. The webs 9 are also similarly recessed at 9^a to permit air circulation. The studding between the terminals of the recesses form lands that are provided with short pieces of lead pipe 13 embedded 65 therein to receive lag screws, such as seen at 14 for securing to the studding metal lath or plaster board 15.

The slab is made as one piece out of concrete formed in a mold of the appropriate 70 form and in the usual manner but preparatory to pouring the concrete two reinforcing rods 16 are provided for each studding member to strengthen those members and before the outer wall member is completely or about 75 poured I lay upon it a sheet of metal lath or so called expanded sheet metal 17 of such size as to leave margins 17^a projecting at the edges of the outer wall member.

In erecting the slab the vertical edges are 80 butted as shown in Fig. 3 and the margins 17^a bent inward and tied together with short pieces of wire as shown in Fig. 5. After the wall has been erected the joints can be 85 pointed up, if necessary, and a coat of stucco or other ornamenting material applied. When the slabs are thus erected the webs 9 afford practically continuous rests for the joist, beams or rafters as suggested at 18 in Fig. 3.

The forms of the parts can be changed 90 somewhat without departing from the gist of the invention as claimed.

What I claim is:

1. A building slab of plastic material including integrally an outer wall member provided with an inwardly extending studding member, a horizontal flange projecting inward from the upper end of said wall, and a horizontal beam-supporting cross web spaced from said end flange and intersecting 95 the studding member.

2. A building slab of plastic material including integrally an outer wall member provided with an inwardly extending studding member, a horizontal flange projecting inward from the upper end of said wall, and a beam-supporting cross web spaced from 100 105

said end flange and intersecting the stud-
ding member, said beam-supporting and
studding member having their inner edges
provided with ventilating recesses and plas-
5 ter-supporting lands between said recesses.

3. A building slab of plastic material in-
cluding integrally an outer wall member

provided with inwardly extending top and
bottom flanges, a studding member on said
wall extending between said flanges and 10
having recesses for horizontal ventilation
and a beam supporting cross web intersect-
ing at right angles the studding member.

CLINTON W. SCHALL.
